D. SILBERMAN

FASTENER STRIP

Filed Sept. 20, 1921

Inventor
David Silberman,

By his Attorneys
Meyers, Cavanagh, Whitehead & Hyde

UNITED STATES PATENT OFFICE.

DAVID SILBERMAN, OF BROOKLYN, NEW YORK.

FASTENER STRIP.

Application filed September 20, 1921. Serial No. 501,943.

To all whom it may concern:

Be it known that I, DAVID SILBERMAN, a citizen of the United States, and resident of Brooklyn, in the county of Kings and State of New York, have invented certain new and useful Improvements in Fastener Strips, of which the following is a specification.

My invention relates in general to apparel and is particularly directed to an improved fastener strip.

As is well known, strips of this type are primarily employed to eliminate the trouble and expense of attaching separate fasteners along the edges of garment closures; and while the type of fastener employed depends somewhat upon the particular use for which the strip is designed, my invention is more particularly adapted to strips carrying hooks and eyes respectively.

A principal object of my invention is to provide a new and improved construction which will provide an unusually strong and firm mounting for the individual fasteners, reducing materially the liability that one or two fasteners on a strip will pull out, without sacrificing cheapness of construction and the attractive appearance of a garment made with these strips.

Another object is to produce a strip which may be very readily and rapidly manufactured by continuously-operating machines of standard types.

Other objects of my invention will be apparent from the following description taken in connection with the accompanying drawings, in which—

Figure 1 is a perspective view of two complementary strips the ends being turned back to show the arrangement, construction and method of interlocking the strips.

Figure 2 is a perspective view of the fastener-carrying element, and

Figure 3 is a transverse section through two connected complementary strips.

Broadly speaking, I attain the above objects by first mounting the hooks or eyes on a strip of strong material; and I then sew this material between plies of a covering strip to produce the finished article. In order to make my construction clear I will first describe the method of constructing a preferred type of strip shown in the drawings.

I first attach a series of fasteners such as the eyes 10 at spaced intervals along a strip,

which preferably is in the form of strong tape. While any means of mounting the eyes may be used, I prefer to employ the rivets 12, as standard machines for riveting these fasteners along the tape in the manner indicated are obtainable. This particular construction and method is much stronger than ordinary cloth and the riveted arrangement eliminates well known difficulties incident to sewing the fasteners in position.

The tape, with the eyes 10 preferably located so as to project beyond an edge thereof, is placed on the cover strip 13 intermediate its edges, and a marginal portion 14 of such strip is folded over the tape in such a way that its edge 15 will extend over rivets 12, and preferably to or slightly beyond the adjacent edge of tape 11. The edge 14 is then sewed through the body of covering strip 13, the stitches 16 preferably passing through the edge of tape 11, thereby binding the tape, fasteners and covering strip securely in finished position. It is preferred that for this purpose a sewing machine be employed which will operate intermittently, so that no stitches will be extended through the portion of the tape occupied by the fasteners; but if desired the stitching may be so arranged across the relatively thin wire portions of the fasteners so that it may be substantially continuous, the needle sliding past the wire of the fastener if it should come down too close thereto.

It will be apparent that numerous methods of sewing the over-turned portion 14 through or over the tape 11 can be employed, and my invention comprehends such variations as will be apparent to one skilled in this art.

When the complementary fastener strip including the covering strip 13^a and fasteners 10^a is similarly constructed the two may be assembled in well known manner as shown in Figures 1 and 3, the fasteners being covered on both sides by portions of the covering strips to protect the garment from damage by the fasteners. However, if this arrangement should not be necessary or desirable, it will readily be understood that the portions of one or both covering strips extending beyond the lines of stitching 16 and 16^a may readily be turned back or substantially dispensed with without interfering with the principal features of my invention above outlined. It will however be likewise apparent that my construction

permits shielding fasteners on both sides, if it is considered preferable.

From the above description it will be apparent that strips embodying my invention may readily be manufactured in any of the various forms which may be required with the greatest speed and cheapness, as the tape 5 may be run through a fastener-attaching machine and thence with the covering strip 10 13 through simple guides to the sewing machine presser foot, only a single seam being required. Furthermore, the construction is extremely strong and durable.

While I have indicated the preferred form 15 of my invention together with certain modifications which will be apparent to those skilled in the art, it will be evident that other changes and re-arrangements may be made within the scope of the appended 20 claims.

I claim:

1. A fastener strip including a tape base strip, a plurality of fasteners of the hook and eye type mounted at spaced intervals 25 on said base strip and projecting beyond an edge thereof, a textile cover strip longitudinally folded and enveloping said base strip, the cover strip extending over the side of the base strip to which the fasteners are

attached substantially to the abovementioned edge thereof, and means extending through superposed portions of the cover strip and base strip for retaining the latter in place. 30

2. A fastener strip assembly comprising a substantially flat, base strip of strong textile material, a plurality of fasteners of the hook and eye type riveted to said strip at spaced intervals, near one edge thereof and with active portions of the fasteners projecting beyond said edge, a cover strip having a relatively wide portion underlying said base strip and the projecting fastener members and another narrower folded portion overlying the base strip at the opposite face thereof enclosing the base strip, and a line of stitching securing the edge of said narrow cover strip portion to the wide cover strip portion, and securing the base strip and fasteners in position with the active fastener members projecting beyond the 40 edge of the narrow cover strip portion and accessible for engagement by co-operative fastener members. 45

Signed at New York, in the county of Kings, and State of New York, this 16th 50 day of September, A. D. 1921.

DAVID SILBERMAN.
